UNITED STATES PATENT OFFICE.

JAMES HUNTER, OF CAMDEN, NEW JERSEY.

SHIELD FOR FIRE-ARMS.

SPECIFICATION forming part of Letters Patent No. 295,013, dated March 11, 1884.

Application filed January 4, 1884. (No model.)

To all whom it may concern:

Be it known that I, JAMES HUNTER, a subject of the Queen of Great Britain and Ireland, and a resident of Camden, New-Jersey, 5 have invented a certain Improved Shield for Fire-Arms, of which the following is a specification.

The object of my invention is to furnish a soldier with an effective shield against the fire 10 of an enemy, the shield being such that when not in use it can be compactly folded and carried without inconvenience, so as to be always at hand when needed. This object I attain in the manner hereinafter set forth, reference being had to the accompanying drawings, in 15 which—

Figure 1 is a view showing one manner in which the shield can be used; Fig. 2, a face view of the shield as it appears when in condition 20 for use; Fig. 3, a view showing the same folded; Fig. 4, an enlarged transverse section of part of the shield; Fig. 5, a perspective view of part of the same; Fig. 6, a view of part of a modified form of shield, and Fig. 7 a further modification.

The invention consists, essentially, of a folding shield applicable to the barrel of a rifle, musket, or carbine, and serving, when expanded, as an effective shield for the head and 30 body of the soldier, and capable, when folded, of being carried at the side with as little inconvenience as that caused by a sword or bayonet. The shield is made of some material capable of resisting rifle or musketry fire at an 35 ordinary range, and the soldier is thus provided with the means of instantly and effectively protecting himself from the fire of an enemy. The shield is, in effect, a portable fortification, more effective than a rifle-pit, so 40 that bold skirmishing movements can with safety be made in the face of an enemy; or, in the case of a general engagement, new lines of attack and defense can be readily formed, or troops moved under an enemy's fire without 45 risk of heavy loss. By raising the shield above the head, the soldier is protected from fragments of bursting shells when subjected to shell-fire, and when used in this way the shield is available also as a protection from the direct rays of the sun when the soldier is on the

march, on guard duty, or otherwise engaged, but not under fire.

Any desired form of folding shield can be used. In Figs. 2 and 3 I have shown, as an instance, a shield made in the same manner 55 as a common form of fan, the shield comprising a series of connected segments, *a*, attached to bars *b*, the pivot-pins of which are adapted to slots in plates *d*, notched for adaptation to the barrel of the fire-arm. The shield, when 60 expanded, should be of sufficient diameter to protect the vital parts of a person using the fire-arm; and the segments may be furnished with sighting-slots, as shown, the bars *b* being preferably of such length as to provide a rest 65 for the shield and gun when the soldier assumes the position shown in Fig. 1. The segments *a* are preferably arranged to overlap and slide on each other, and are guided and retained by means of a pin, *f*, on each segment, adapted to a slot, *g*, in the adjoining segment, the slots being recessed for the reception of the heads of the pins, as shown in Fig. 5. The segments may, however, be constructed 70 so as to fold, and be provided with hinge-joints, as in Fig. 6; or the shield may be made of a continuous web of flexible material—such, for instance, as cloth with a metallic warp or weft or small interlocked links—and it may be made to operate in the same manner as an 75 umbrella, as shown in Fig. 7. In fact, I wish it to be distinctly understood that the main feature of my invention is not limited to any particular construction of folding shield, or to any special means of folding or expanding the 80 same, nor is it necessary that the shield should be detachable from the barrel of the fire-arm, although this is of course preferred.

I am aware that it has been proposed to make shields of metal plates constructed for 90 being hinged together at the edges, each plate being of large size, and the series of plates being intended to rest upon the ground, so as to serve as a substitute for an earth-work or like fortification; but my invention is entirely distinct from this, as each shield is a complete self-contained device capable of being folded into small compass and carried by the fire-arm when in use, but of such a character as not 95 to interfere with the ordinary uses of the arm. 100

Without therefore claiming, broadly, a portable shield or breastwork, I claim as my invention—

1. As a new article of manufacture, a bullet-proof shield constructed so as to be folded into compact form, as described, and having, when expanded, a central opening for the reception of the barrel of a fire-arm, as set forth.
2. The combination of a fire-arm with a bullet-proof shield attached to and carried by the barrel of said fire-arm, and capable of being folded, as set forth.
3. The combination of a fire-arm with a folding shield of bullet-proof material attached to and carried by the barrel of the fire-arm, but constructed so as to be readily detached therefrom, as set forth.
4. The within-described folding shield for

fire-arms, the same comprising a series of connected segments, *a*, of bullet-proof material, 20 side bars *b*, and a slotted plate, *d*, adapted to the barrel of the fire-arm, as set forth.

5. The combination, in a fire-arm shield, of the segments *a*, overlapping each other and having pins *f* and slots *g* for their guidance and retention, as set forth.

6. The combination of the fire-arm with the folding shield having opposite projecting bars *b b*, serving as a rest, as set forth.

In testimony whereof I have signed my name 30 to this specification in the presence of two subscribing witnesses.

JAMES HUNTER.
